(57) **CLAIM**

The ornamental design for a travel adapter, as shown and described.

DESCRIPTION

FIG. 1 is a front view of a travel adapter showing the new design;

FIG. 2 is a rear view thereof;

FIG. 3 is a left side view thereof;

FIG. 4 is a right side view thereof;

FIG. 5 is a top plan view thereof;

FIG. 6 is a bottom plan view thereof;

FIG. 7 is a front-bottom-right perspective view thereof; and, FIG. 8 is a rear-bottom-left perspective view thereof.

The broken lines in the drawings depict portions of the travel adapter that form no part of the claimed design.

1 Claim, 8 Drawing Sheets
